United States Patent Office.

WILLIAM RUNTE, OF NEW YORK, N. Y.

Letters Patent No. 63,308, dated March 26, 1867.

IMPROVEMENT IN TOOL HANDLES.

The Schedule referred to in these Letters Patent and making part of the same.

TO ALL WHOM IT MAY CONCERN:

Be it known that I, WILLIAM RUNTE, of the city, county, and State of New York, have invented a new and improved Tool Handle; and I do hereby declare that the following is a full, clear, and exact description thereof, which will enable others skilled in the art to make and use the same, reference being had to the accompanying drawings, forming a part of this specification, in which—

Figure 1 is a side view of my invention partly in section.

Figure 2 is a portion of a sectional view of the same.

The object of this invention is to so arrange a tool handle that all kinds of shoemakers' and saddlers' tools may be easily held therein, and that they may be easily removed therefrom and replaced without trouble.

The invention consists in securing the tool to a conical wooden plug, which is inserted into a tapering tube, said tube being screwed into the ferrule, which is firmly secured to the handle. The tool is held by the pressure of the upper surface of the handle upon the base of the conical plug, which is thereby firmly pressed into the tapering tube. All kinds of shoemakers' and saddlers' tools may be arranged in such a handle, each tool being secured to a conical plug. They may then all be adapted to one single handle, and may be easily removed or replaced.

A is the wooden handle; B, the ferrule, which is firmly secured to it; C is the tool to be held by the handle. The ferrule projects above the handle, as shown, and is provided either with a male or female screw-thread. The tool is firmly secured to the conical plug D, which is inserted from below into the tapering tube E. The latter is then screwed to the ferrule. The plug D projects a little beyond the lower end of the tube E, as shown, so that, by the pressure of the inner end *a* of the handle A upon the base end of the plug, the said plug is immovable in the tube E; but as soon as the latter is screwed off, the cone can be easily removed therefrom with the tool, and a new tool inserted. The ferrule B may be provided with a plate, *b*, so as to cover the end of the handle A, as shown in fig. 2; or it may simply be a tube, as shown in fig. 1. In fig. 1 the ferrule is shown with a female screw-thread, while in fig. 2 it is provided with a male thread.

Having thus described my invention, what I claim as new, and desire to secure by Letters Patent, is—

The combination of the plug D, and the adjustable ferrule or tube E, with the tool handle, substantially as and for the purpose herein shown and described.

WM. RUNTE.
